VALVE TAPPET PUSH ROD

Jesse T. Wright, Bountiful, Utah

Application June 12, 1952, Serial No. 293,178

8 Claims. (Cl. 123—90)

1

This invention relates in general to valve tappet push rods, and more particularly to a self-adjusting push rod that will expand longitudinally to compensate for wear.

The primary object of this invention is to provide an improved push rod for internal combustion engines which is provided with a slack take-up device whereby a rocker arm or other tappet may be in constant engagement with a valve stem and at the same time permitting the existence of a clearance between the positive drive of the cam shaft and the end of the valve stem.

Another object of this invention is to provide an improved push rod adapted for use with internal combustion engines having overhead valves whereby the lost motion between the rocker arms and the valve stems is eliminated, thereby eliminating excessive noise resulting from the striking of the rocker arms on the ends of the valve stems.

Another object of this invention is to provide an improved push rod for use with internal combustion engines, said push rod being formed in sections which are urged apart by spring means, the movable portions of said sections being pressure lubricated.

A further object of this invention is to provide an improved push rod for internal combustion engine valve assemblies, said push rod being sectional and having portions thereof urged apart by a spring element, said push rod being provided with means for locking the spring element in an inoperative position whereby the clearance between an associated rocker arm and valve stem may be properly adjusted.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application and in which:

Figure 1 is a fragmentary front elevational view of a conventional overhead valve internal combustion engine, portions of the block and valve cover of the engine being broken away and shown in section in order to clearly illustrate the construction of the valve assembly and the push rod, which is the subject of this invention;

Figure 2 is an enlarged fragmentary longitudinal vertical sectional view taken substantially upon the plane indicated by the section line 2—2 of Figure 1 and shows the elements of the push rod in operative positions;

Figure 3 is an enlarged transverse horizontal

2

sectional view taken substantially upon the plane indicated by the section line 3—3 of Figure 2 and shows the normal relationship of locking pins for portions of the push rod assembly;

Figure 4 is an enlarged fragmentary front elevational view of an upper portion of the push rod of Figure 1 and its associated rocker arm, the engine block and valve cover being shown in section, the spring for urging portions of the push rod apart being retained in an inoperative position by a locking device; and

Figure 5 is an enlarged transverse horizontal sectional view taken substantially upon the plane indicated by the section line 5—5 of Figure 4 and shows the relation of a pin carried by the locking device when the same is in a spring locking position.

Similar characters of reference designate similar or identical elements and portions throughout the specification and throughout the different views of the drawings.

Referring now to the drawings in detail, it will be seen that there is illustrated in Figure 1 a conventional internal combustion engine, which is referred to in general by the reference numeral 10, of the overhead valve type. The engine 10 includes a block 12 in which is mounted for rotation a cam shaft 14 having in engagement therewith a cam follower 16. Secured to the top of the block 12 is a head 18 on which is mounted a rocker arm shaft support 20 and a longitudinally extending rocker arm shaft 22. Mounted on the rocker arm shaft 22 for pivotal movement is a rocker arm 24 which has one arm thereof in vertical alignment with the cam follower 16 and operatively connected thereto by a push rod 26. The other arm of the rocker arm 24 is adapted to engage the upper end of a valve stem 28.

It will be understood that the valve stem 28 has integral with the lower end thereof a valve (not shown) which is actuated by the rocker arm 24. In order that the valve stem and its associated valve may be raised to a closed position upon upward movement of the rocker arm 24, the valve stem has surrounding the same a valve spring 30 whose lower end bears against the upper surface of the head 18 and whose upper end bears against a keeper 32.

In order that proper seating of the valve may be assured, the upper end of the valve stem 28 is slightly spaced from a tappet portion 34 of the rocker arm 24 when the tappet portion 34 is in its uppermost position and the valve is seated. While the clearance between the upper end of the valve stem 28 and the tappet 34 is only a few

thousandths of an inch, the striking of the tappet 34 in a downward stroke against the upper end of the valve stem 28 results in a noisy chatter. Also, the upward movement of the valve into engagement with its seat also results in additional noise.

Referring now to Figure 2 in particular, it will be seen that in order to retain the desired clearance between the positive drive elements for the valve stem 28 and at the same time to eliminate actual clearance between the tappet 34 and the upper end of the valve stem 28 whereby the chattering may be greatly reduced, the push rod 26 is sectional. The push rod 26 includes an upper tubular portion 36 which has engaged in the upper end thereof a reduced lower portion 38 of a rocker arm engageable member 40. The rocker arm engageable member 40 is provided with a shoulder 42 which is adapted to engage the upper end of the tubular portion 36 to insure a positive drive for pivoting the rocker arm 24. Disposed in the lower end of the tubular portion 36 is a coil spring 44 which urges the member 40 upwardly with respect to the upper end of the tubular portion 36 whereby the tappet 34 is moved into engagement with the upper end of the valve stem 28 and the clearance eliminated at that point. However, it will be understood that the shoulder 42 of the member 40 moves away from the upper end of the tubular portion 36 a distance equal to the clearance normally provided between the tappet 34 and the valve stem 28. Inasmuch as the strength of the valve spring 30 is much greater than that of the coil spring 44, the valve associated with the valve stem 28 will be permitted to seat.

In order that the normal clearance between the tappet 34 and the upper end of the valve stem 28 may be adjusted, the portion of the rocker arm 24 overlying the member 40 is provided with a vertically extending threaded bore 46 in which is mounted an adjustable screw 48 having a spherical lower end 50. The spherical lower end 50 is received in a complementary seat 52 in the upper end of the member 40 and the clearance between the tappet 34 and the valve stem 28 may be adjusted by threading the screw 48 in or out of the threaded bore 46. The screw 48 is locked in its adjusted position by a lock nut 54 threadedly engaged on the upper end thereof and engaging the upper surface of the rocker arm 24.

While the above described valve assembly will operate in a suitable manner, it will be seen that the upward urging of the member 40 by the coil spring 44 results in the engagement of the tappet 34 with the upper end of the valve stem 28 whereby the normal clearance between the two cannot be measured. Inasmuch as the internal combustion engine 10 will not operate properly unless the valves are properly set, it is desirable to provide means for rendering the coil spring 44 inoperative whereby the shoulder 42 of the member 40 engages the upper end of the tubular portion 36 and the clearance between the tappet 32 and the upper end of the valve stem 28 actually exists. In order to do so, the tubular portion 36 is provided with a spacer element 56 disposed between the upper end of the coil spring 44 and the lower end of the reduced portion 38 of the member 40. During normal operation of the push rod 26, the upward force of the coil spring 44 is transmitted to the member 40 through the spacer 56. The spacer 56 is provided with a transversely extending pin 58 which is positioned with end portions thereof extending outwardly

through diametrically opposite vertical slots 60. Inasmuch as the end portions of the pin 58 are disposed within vertical slots 60, the spacer 56 is free to reciprocate in a vertical direction within the tubular portion 36. In order that the spring 44 may be locked in an inoperative position, the slots 60 are provided with notches 62 adjacent the lower ends thereof in which the end portions of the pin 58 may be disposed. It will be understood that the notches 62 are positioned below the normal position of the pin 58 whereby, when the same is moved downwardly into engagement therewith, the coil spring 44 is readily compressed. The notches 62 are so spaced from the normal position of the pin 58 whereby when the coil spring 44 and the spacer 56 are locked in position, the lower end of the released portion 38 of the member 40 is spaced vertically above the upper end of the spacer 56 and the shoulder 42 of the member 40 is in engagement with the upper end of the tubular portion 36. After the valve has been adjusted, the pin 58 is rotated a slight angle back into the slot 60 where the same is free to reciprocate vertically. It will be noted that the member 40 is also locked to the tubular portion 36 by a pin 64 which has end portions disposed within the slot 60.

Inasmuch as the reduced portion 38 of the member 40, the spacer 56 and the coil spring 44 reciprocate within the tubular portion 36, it is desirable that the elements be supplied with oil for lubricating purposes. Therefore, the rocker arm 24 is provided with an oil feed bore 66 which communicates with a transversely extending oil passage 68 in the screw 48. The screw 48 is provided with a longitudinal oil passage 70 which opens through the lower end of the spherical portion 50 and communicates with a longitudinal oil passage 72 through the member 40. The lower end of the longitudinal oil passage 72 communicates with a transversely extending oil passage 74 which applies oil to the interior of the tubular portion 36. In order that oil may drain from the interior of the tubular portion 36, the bottom thereof is provided with a drain opening 76.

It will be understood that the push rod 26 may be used to replace existing push rods and that the same is not limited to use with the internal combustion engine illustrated in Figure 1.

The operation of this device will be understood from the foregoing description of the details thereof, taken in connection with the above recited objects and drawings. Further description would therefore appear to be unnecessary.

Minor modifications of the device, varying in minor details from the embodiment of the device illustrated and described here, may be resorted to without departure from the spirit and scope of this invention, as defined in the appended claims.

Having described the invention, what is claimed as new is:

1. A push rod for actuating a valve assembly comprising an elongated rod having a lower end engageable with a cam follower, the upper portion of said elongated rod being tubular, a rocker arm engageable member carried by the upper end of the tubular upper portion, a spring carried by said tubular portion urging said member into engagement with the associated rocker arm, locking means for temporarily rendering said spring inoperative whereby the valve assembly may be adjusted to obtain the desired clearance.

2. A push rod for actuating a valve assembly comprising an elongated rod having a lower end

engageable with a cam follower, the upper portion of said elongated rod being tubular, a rocker arm engageable member carried by the upper end of the tubular upper portion, a spring carried by said tubular portion urging said member into engagement with the associated rocker arm, locking means for temporarily rendering said spring inoperative whereby the valve assembly may be adjusted to obtain the desired clearance, said tubular portion being provided with means for releasably retaining a portion of said member within said tubular portion for sliding movement.

3. A push rod for actuating a valve assembly comprising an elongated rod having a lower end engageable with a cam follower, the upper portion of said elongated rod being tubular, a rocker arm engageable member carried by the upper end of the tubular upper portion, a spring carried by said tubular portion urging said member into engagement with the associated rocker arm, locking means for temporarily rendering said spring inoperative whereby the valve assembly may be adjusted to obtain the desired clearance, said locking means being disposed within said tubular portion.

4. A push rod for actuating a valve assembly comprising an elongated rod having a lower end engageable with a cam follower, the upper portion of said elongated rod being tubular, a rocker arm engageable member carried by the upper end of the tubular upper portion, a spring carried by said tubular portion urging said member into engagement with the associated rocker arm, locking means for temporarily rendering said spring inoperative whereby the valve assembly may be adjusted to obtain the desired clearance, said locking means being disposed within said tubular portion between said member and said spring.

5. A push rod for actuating a valve assembly comprising an elongated rod having a lower end engageable with a cam follower, the upper portion of said elongated rod being tubular, a rocker arm engageable member carried by the upper end of the tubular upper portion, a spring carried by said tubular portion urging said member into engagement with the associated rocker arm, locking means for temporarily rendering said spring inoperative whereby the valve assembly may be adjusted to obtain the desired clearance, said locking means including a transversely extending pin carried by said tubular member above said spring, said pin having end portions normally positioned in diametrically opposite vertical slots, each of said slots being provided with notches for receiving end portions of said pins to lock said spring in a compressed state.

6. A push rod for actuating a valve assembly comprising an elongated rod having a lower end engageable with a cam follower, the upper portion of said elongated rod being tubular, a rocker arm engageable member carried by the upper end of the tubular upper portion, a spring carried by said tubular portion urging said member into en-

gagement with the associated rocker arm, locking means for temporarily rendering said spring inoperative whereby the valve assembly may be adjusted to obtain the desired clearance, said locking means including a transversely extending pin carried by said tubular member above said spring, said pin having end portions normally positioned in diametrically opposite vertical slots, each of said slots being provided with notches for receiving end portions of said pins to lock said spring in a compressed state, said notches being below the normal position of the pin.

7. A push rod for actuating a valve assembly comprising an elongated rod having a lower end engageable with a cam follower, the upper portion of said elongated rod being tubular, a rocker arm engageable member carried by the upper end of the tubular upper portion, a spring carried by said tubular portion urging said member into engagement with the associated rocker arm, locking means for temporarily rendering said spring inoperative whereby the valve assembly may be adjusted to obtain the desired clearance, said locking means including a transversely extending pin carried by said tubular member above said spring, said pin having end portions normally positioned in diametrically opposite vertical slots, each of said slots being provided with notches for receiving end portions of said pins to lock said spring in a compressed state, said pin being carried by a spacer element disposed between and normally in engagement with said member and said spring.

8. A push rod for actuating a valve assembly comprising an elongated rod having a lower end engageable with a cam follower, the upper portion of said elongated rod being tubular, a rocker arm engageable member carried by the upper end of the tubular upper portion, a spring carried by said tubular portion urging said member into engagement with the associated rocker arm, locking means for temporarily rendering said spring inoperative whereby the valve assembly may be adjusted to obtain the desired clearance, said locking means including a transversely extending pin carried by said tubular member above said spring, said pin having end portions normally positioned in diametrically opposite vertical slots, each of said slots being provided with notches for receiving end portions of said pins to lock said spring in a compressed state, said member having a lower portion thereof telescopically received within the upper end of the tubular portion and retained therein by a second pin having end portions disposed in said slots.
